UNITED STATES PATENT OFFICE.

WALTER R. ADDICKS, OF BROOKLINE, MASSACHUSETTS, AND JOHN H. WILLIAMSON, OF BETHEL, CONNECTICUT; SAID WILLIAMSON AS-SIGNOR TO SAID ADDICKS.

BOILER.

SPECIFICATION forming part of Letters Patent No. 634,127, dated October 3, 1899.

Application filed November 27, 1897. Serial No. 659,983. (No model.)

To all whom it may concern:

Be it known that we, WALTER R. ADDICKS, residing in Brookline, in the county of Norfolk and State of Massachusetts, and JOHN H. WILLIAMSON, residing in Bethel, in the county of Fairfield and State of Connecticut, have invented an Improvement in Boilers, of which the following description, in connection with the accompanying drawings, is a specification, like letters on the drawings representing like parts.

This invention relates to a boiler or steam-generator especially designed and adapted for use in connection with a carbureted-water-gas-producing apparatus for the utilization of the heated gases from said apparatus.

Prior to this invention it has been proposed to utilize the heated gases referred to by passing them through a boiler; but, so far as we are aware, these attempts have not been commercially successful, owing to the fact that the heating-surfaces of the boiler soon become coated over with a deposit of foreign matter held in suspension or in combination with the gases and which solidifies or bakes rapidly onto said heating-surfaces and forms a non-heat-conducting coating for the boiler, which diminishes the efficiency of the boiler and soon renders the same practically useless.

This is especially true when the boiler is of tubular construction, in which the hot gases pass through the tubes, for, by reason of the deposit referred to, these tubes become wholly or partially closed in a substantially short time.

Prior to this invention we are not aware of a boiler which is so constructed as to permit of its use commercially in conjunction with a water-gas-producing apparatus, owing to the fact that no provision has been made whereby the boiler proper could be removed without disturbing its casing or shell, or vice versa, to permit of access to the coated surfaces of the boiler for the purpose of removing the deposit or coating on said surfaces.

Our invention has for its object to provide a boiler which is capable of being removed from its casing or shell, or vice versa, and replaced by a clean or new boiler or casing with substantially little inconvenience, ex-

pense, or delay. These and other features of this invention will be pointed out in the claims at the end of this specification.

Figure 1 is a vertical section of a boiler embodying this invention, and Fig. 2 a top or plan view of the boiler shown in Fig. 1.

In the present instance we have chosen to illustrate our invention in its preferred form—namely, with the casing stationary and the boiler proper removable therefrom without disturbing the side walls of the casing.

Referring to Fig. 1, A represents the side walls of the outside shell or casing, which may be of any desired or suitable construction, and preferably an iron or steel jacket ⁶⁵ a, provided with a lining a', of fire-brick or other suitable refractory material. The casing or shell is provided with a bottom A' and a top A², both of a construction similar to the side walls and one or both of which is removable attached to the said side walls.

The casing or shell referred to contains within it the boiler proper, preferably of the form and construction herein shown and consisting of a preferably cylindrical body a⁴, ⁷⁵ preferably longer than the casing or shell and extended, as herein shown, through and beyond the top A² and bottom A' of said casing. The body a⁴ is provided, as herein shown, with removable ends or heads a⁶ a⁷, ⁸⁰ the head a⁷ having, as shown, a manhole a⁸, which in practice will be closed by a suitable cover. (Not shown.)

The body a⁴ of the boiler herein shown is provided with a plurality of projecting hollow tubes or pipes b, closed at their outer ends and preferably arranged about the body a⁴ to obtain a staggered and spiral effect. The body a⁴ and its attached tubes or pipes b are of such size as will permit of their being ⁹⁰ removed from within the casing or shell without disturbing the side walls A of the same.

The removal of the boiler proper may be effected by removing either the top A² or the bottom A' of the outside casing, depending upon the location of the boiler within the gas-works. In the present instance both the top A² and bottom A' are shown as detachably secured to the side walls A of the casing, the metal jacket or plate b' for the top being ¹⁰⁰

shown as secured to the metal jacket a by bolts b^2 , while the bottom A' is shown as supported upon an angle-iron ring b^3 , riveted or bolted to a like ring b^4 , attached to the metal jacket a .

In order to permit of expansion and contraction of the boiler proper and secure a gas-tight joint at the point or points where the boiler extends through the top A^2 or bottom A' , a suitable packing is provided.

In the present instance the boiler extends through both the top A^2 and bottom A' of the casing, and a packing-ring b^{10} is provided for the top A^2 and a packing-ring b^{12} is provided for the bottom A' .

The packing-rings $b^{10} b^{12}$ may be secured in position in any suitable or desired manner, and, as herein shown, the packing b^{10} is secured by means of a flanged ring b^{13} , attached to the top of the casing, and a second flanged ring b^{14} , attached to the ring b^{13} , as by bolts b^{15} . The packing b^{12} may be secured in a like manner by flanged rings $b^{16} b^{17}$ and bolts b^{18} . The boiler is provided, as shown, with a steam-dome b^{20} , formed by the upper end of the body a^4 , and a cross partition-wall b^{21} , having an outlet-pipe b^{22} from the steam and water chamber b^{23} into the steam-dome b^{20} , and to which outlet-pipe is secured by bolts b^{24} a cap b^{25} , into which the coupling-pipe b^{26} is screwed, the pipe b^{26} being extended through the top a^6 of the boiler and connected by a coupling or fitting b^{30} to the main steam-outlet pipes b^{31} . The pipe b^{26} , as shown, is screwed through the crown-sheet or top a^6 and a reinforcing-plate b^{32} .

The outside casing or setting for the boiler proper is supported on a suitable foundation, and in the present instance the said casing is shown as resting upon I-beams b^{33} , which in turn rest upon a suitable foundation, which may be a circular beam b^{34} , which latter may be supposed to form part of the floor of the room in which the boiler is placed. This floor may be the basement of the gasworks or it may be above the basement, which latter is preferred, and when so located the floor may have a suitable opening through which the boiler proper may be lowered down into the basement after making the necessary disconnections of the pipes and removing the bottom A' of the outside casing or shell.

For the purpose just specified the top A^2 of the boiler may have attached to it suitable plates or pieces b^{40} (see Fig. 2) for the attachment of suitable tackle. When the boiler is lowered into the basement or to the floor below, it is accessible for cleaning either by hand or machinery, and when properly cleaned it may be again hoisted into its casing; but, if desired, a second and clean boiler can be hoisted into place within the casing in a comparatively short time, and when properly positioned the pipe connections may be made and the bottom A^2 replaced and secured gas-tight.

The outside casing for the boiler proper is provided, as shown, with a gas-inlet b^{41} in its side wall A , near its bottom A' , and with a gas-outlet b^{42} in its top A^2 and is further provided in its side walls A with manholes b^{43} , which are closed gas-tight by suitable covers b^{44} .

The top A^2 of the boiler-casing may have extended across it suitable bars b^{50} to resist the pressure of the gas within the said casing and which are removably attached to said casing.

In the present instance the bottom of the boiler proper, a^4 , is supposed to be anchored—that is, it is supposed to rest on a solid support, which may be cross-bars resting on the beam or bar b^{34} —while the top of the boiler is free to respond to the variations in temperature, suitable provision being made in practice in any usual way for the steam-pipes to move with the boiler.

In order to avoid dead-pockets within the casing for the accumulation of air and gas, which might form an explosive mixture, the corners of the casing are made rounding, as shown in Fig. 1.

From the above description it will be seen that the boiler proper may readily be removed from its casing in a comparatively short time without destroying or partially destroying said casing, and, further, that it may be removed from either end. We have herein shown the boiler proper extended through both the top and bottom; but we do not desire to limit ourselves in this respect, as it may be extended only through one end. The end of the boiler which is free to respond to variations in temperature is provided with a suitable gas-tight packing to prevent the escape of gas out of said casing, the gas being under pressure in said casing, which is thus rendered pressure-tight.

We claim—

1. In a boiler of the character described, the combination with an outside pressure-tight casing provided with a gas-inlet and a gas-outlet, and having one of its ends removable, of the boiler proper located within said casing and having one end extended through one end of said casing, substantially as and for the purpose specified.

2. In a boiler of the character described, the combination with an outside pressure-tight casing provided with a gas-inlet and with a gas-outlet, and a boiler located within said casing and anchored at one end and having its other end free to respond to variations in temperature, substantially as described.

3. In a boiler of the character described, the combination with an outside pressure-tight casing provided with a gas-inlet and with a gas-outlet, and a boiler located within said casing and having one end anchored and its other end extended loosely through said casing, and a gas-tight packing for the loose end of said boiler, substantially as described.

4. In a boiler of the character described, the combination with an outside pressure-tight

casing provided with a gas-inlet and with a
gas-outlet, and a boiler located within said cas-
ing and anchored at one end and having its
other end free to respond to variations in tem-
perature, and means to render the casing gas-
tight at the unanchored end of the boiler, sub-
stantially as described.

In testimony whereof we have signed our

names to this specification in the presence of
two subscribing witnesses.
